UNITED STATES PATENT OFFICE.

AARON V. LEA, OF BISBEE, ARIZONA, ASSIGNOR OF ONE-HALF TO JOSEPH LEA, OF BISBEE, ARIZONA.

EGG-CARRIER.

1,343,629.

Specification of Letters Patent. Patented June 15, 1920.

Application filed March 29, 1917. Serial No. 153,422.

To all whom it may concern:

Be it known that I, AARON V. LEA, a citizen of the United States, residing at Bisbee, in the county of Cochise and State of 5 Arizona, have invented certain new and useful Improvements in Egg-Carriers, of which the following is a specification.

This invention relates to an egg carrier and the principal object of the invention is 10 to provide means for safely supporting the eggs, while at the same time providing means for keeping the carrier cool.

Another object of the invention is to provide means for insulating the carrier, so 15 as to prevent the transmission of heat thereto.

Another object of the invention is to surround the egg compartments in the carrier by an air space.

20 Another object of the invention is to provide a device of this character which is simple and durable in construction, reliable and efficient in operation, and one which can be manufactured and placed upon the market at a minimum cost.

To accomplish the above and various other objects, my invention consists essentially of a carrier or receptacle with compartments therein for containing the eggs 30 and means in the carrier for receiving ice to keep the carrier cool, means for insulating the carrier and means for providing an air space around the walls of the carrier.

The invention also consists in certain 35 other features of construction and in the combination and arrangement of the several parts, to be hereinafter fully described and specifically pointed out in the appended claims.

40 In describing my invention in detail, reference will be had to the accompanying drawings, wherein like characters denote like or corresponding parts throughout the several views, and in which:

45 Figure 1 is a plan view, with the cover removed.

Fig. 2 is a longitudinal section.

Fig. 3 is a side view of one of the trays partly broken away.

50 Fig. 4 is a vertical section of the receptacle 1 showing the insulated construction thereof.

In these drawings, the receptacle is indicated by the numeral 1 and I prefer to

make this receptacle of metal, having a 55 layer of wood 14 next to the metal, then a layer of cork 15 or some other insulating material and its interior wall 16 formed of metal.

The receptacle is provided with two handles 2 and a cover 3. Within the receptacle 1, I provide a frame 3' consisting of four sides, all of which are spaced from the walls of the receptacle 1 to permit rapid circulation of air entirely around and through the 65 frame. At each end of this frame, I form an egg compartment 4 and 5, and an ice compartment 6 is located between the egg compartments and extends transversely of the frame 3'. By spacing the frame from 70 the walls of the receptacle, an air space 7 is provided. The frame is also spaced from the top of the receptacle and from the bottom of the same by means of horizontal cross block 8 so as to provide an air space 9 75 between the bottom of the receptacle and the bottom of the frame. A pair of vertical blocks 8' are secured to each wall of the receptacle and each block is arranged adjacent the end of its respective wall. The two 80 adjacent blocks on adjacent walls of the receptacle snugly engage two adjacent walls of the frame 3' for spacing said frame from the side walls of the receptacle.

I prefer to place the eggs in separate 85 layers in cases 10, each case being formed of sheet metal having holes 11 therein, and their bottoms formed of wire gauze 12. 12' are the usual partitions of card board.

As shown, the cases are located one above 90 the other in the compartment. The ice compartment is formed of perforated sheet metal and is provided with drain tubes 13 for draining the water therefrom. It will also be noted that the perforations in the 95 sides of the ice compartment align with the holes 11 in the respective trays, and accordingly permits the cool air to pass directly from the interior of the ice compartment throughout the entire length of the trays, 100 and also that the wire mesh bottoms of the trays permit the cool air to circulate vertically as well as horizontally of the receptacle to completely aerate each egg. The cases or trays 10 are of such length, that 105 one end thereof abuts with the end of the tray abuts with the wall of the ice compartment,

and accordingly the openings in the trays and ice compartment are always kept in alinement.

By my invention the eggs are not only carried safely against breakage, but they are prevented from being spoiled in hot weather by means of the ice cooled air circulating around them, the air remaining cool, not matter how hot the day, on account 10 of the insulated walls of the receptacle.

It is thought from the foregoing that the advantages and novel features of my invention will be readily apparent.

I desire it to be understood that I may 15 make slight changes in the construction and in the arrangement and combination of the several parts, provided such changes fall within the scope of the appended claims.

I claim as my invention:

20 1. An egg carrier comprising a receptacle, a frame consisting of four side walls spaced from the side walls and the top and bottom of the receptacle, an egg compartment in each end of the frame, an ice compartment 25 in the center of the frame and between said egg compartments, said ice compartment having a plurality of horizontal rows of perforations in the side walls thereof, a plurality of egg trays having screen bottoms 30 and a horizontal series of perforations in their walls, the outside end of each tray abutting with the end wall of the frame while the inner end wall of each tray abuts with the side wall of the ice compartment to 35 prevent movement of the trays and to retain the perforations in the inner end walls of the trays in alinement with the perforations in the ice compartment.

2. An egg carrier comprising a rectangular receptacle, a pair of vertical blocks upon 40 each wall adjacent the ends of the walls, horizontal blocks on the bottom of the receptacle each one being arranged adjacent the corners of the receptacle, a pair of

spaced horizontal blocks on the bottom of 45 the receptacle adjacent the center thereof, a rectangular frame resting upon the horizontal blocks and abutting with the vertical blocks, a perforated ice compartment arranged centrally of the receptacle and supported from the bottom thereof by the 50 spaced horizontal blocks adjacent the center of the bottom, a plurality of egg trays arranged one upon the other and upon each side of the ice compartment, said egg trays 55 having a screened bottom and perforated walls, the bottom tray of each set of trays being supported upon one horizontal block and one central horizontal block so that one end of each tray abuts with the end wall or 60 the frame and the other end abuts with the ice compartment for preventing movement of several trays and to retain the perforations in the egg trays and the ice compartments in alinement with one another. 65

3. An egg carrier comprising a receptacle, a frame arranged within the receptacle and spaced from the inner walls thereof, egg compartments in each end of said frame, an ice compartment arranged in said frame 70 between said egg compartments, said ice compartment being provided with a plurality of horizontal rows of perforations, egg trays in said egg compartments and having their walls provided with a horizontal row 75 of perforations and one end of said trays abutting with the end walls of the frame while the opposite end walls of the trays abut with the side walls of the ice compartment to retain the perforations in the trays 80 and ice compartment in alinement with one another.

In testimony whereof I affix my signature in presence of two witnesses.

AARON V. LEA.
